CLAIM

The ornamental design for a mount adapter bracket, as shown and described.

DESCRIPTION

FIG. 1 shows a top perspective view of the mount adapter bracket.

FIG. 2 is a front view of the mount adapter bracket.

FIG. 3 is a back view of the mount adapter bracket.

FIG. 4 is a left side view of the mount adapter bracket.

FIG. 5 is a right side view of the mount adapter bracket.

FIG. 6 is a top view of the mount adapter bracket; and,

FIG. 7 is a bottom view of the mount adapter bracket.

The broken lines in the drawings depict portions of the bracket that form no part of the claimed design.
